G. H. GILMAN

DRILLING MACHINE

Filed March 13, 1923

Inventor:
George H. Gilman
by Every Booth Journey & Farney
Attys

UNITED STATES PATENT OFFICE.

GEORGE H. GILMAN, OF BELMONT, MASSACHUSETTS.

DRILLING MACHINE.

Application filed March 13, 1923. Serial No. 624,845.

My invention relates to fluid pressure motors and gearing and particularly but not exclusively to a hammer rock drill having a motor and gearing for rotating the chuck.

5 My invention will be best understood from the following description when read in the light of the accompanying drawings showing one specific embodiment of my invention selected for illustrative purposes, while 10 the scope of my invention will be more particularly pointed out in the appended claims.

In the drawings:—

Fig. 1 is a longitudinal section of the forward part of a rock drill;

15 Fig. 2 is a section on the line 2—2 of Fig. 1; and

Fig. 3 is a section on the line 3—3 of Fig. 2.

Referring to the drawings and to the preferred embodiment of my invention I have shown a casing in which is mounted for reciprocation a hammer piston 1 having the forward extension 3 which at the end of the forward stroke of the hammer piston strikes 25 the end of the shank 5 of the drill steel 7. Rotatably mounted in the forward end of the casing is a sectional chuck 9 which carries the shank of the drill steel in such manner that when the chuck rotates the drill 30 steel must rotate with it.

As shown in the drawings the casing hereinbefore referred to includes a rearward cylinder section 10 and a forward cylinder section 11 for receiving the hammer piston, a 35 section 13 for receiving the chuck, and separating the sections 11 and 13 a section 15 for receiving the mechanism for rotating the chuck. All these sections as will be understood by those skilled in the art are 40 held in assembled relation by the four through bolts 19.

The rearward end of the chuck as illustrated has an external bearing 21 at the front end of the cylinder section 11, and forwardly of this bearing the chuck is provided with the external gear teeth 23. Surrounding the gear teeth 23 is a block 25 which generally stated is of quadrilateral exterior and is formed with an opening provided with the internal gear teeth 27 in mesh with the external gear teeth 23 on the chuck. Surrounding the block 25 is a member 29 which generally stated is in the form of a rectangular ring having at opposite sides rec-

tangular projections 31 the upper and lower flat sides of which slidably fit the upper and lower sides of recesses or chambers 33 in the casing section 15, while the forward and rearward sides respectively slidably fit the forward end face 35 of the cylinder section 11 and the rearward end face 37 of the casing section 13. Internally the opposite vertical sides of the member 29 as viewed in Fig. 2 slidably fit the exterior of the block 25 as indicated at 39.

Rotatively mounted in the forward end of the cylinder section 11 I have shown four pins 41 which are formed with reduced eccentric portions 43 projecting into and supporting the block 25. By this construction 70 rotation of the block 25 is prevented and it is constrained to gyrate in an orbit about the axis of the chuck. For causing gyration of the block 25 I alternately admit and exhaust motive fluid to and from the opposite 75 chambers 33 and to and from the chambers 45 between the upper and lower sides of the block 25 and member 29 as viewed in Fig. 2.

For supplying the chambers 45 with motive fluid I have shown the casing section 11 provided with passages 47 which in any convenient manner lead from the motive fluid supply intake for the machine and terminate in passages 49 opening on the forward end face 35 of the casing section 11. Formed 80 in the block 25 are passages 51 which lead from the side of the block in contact with the face 35 and open into the chambers 45.

For exhausting the motive fluid from the chambers 45 I herein form through the 90 wall of the member 29 passages 53 which as clearly shown in Fig. 2 are adapted to be moved into registry with grooves 55 at the exterior corners of the block 25 and thereby place the chambers 45 into communication with the chambers 57 at the exterior of the member 29, the chambers 57 permanently communicating with the atmosphere by way of passages 59 formed through the wall of the casing section 15.

For admitting motive fluid to the chambers 33 I herein form through the casing section 11 a pair of passages 61 one of which is shown in Fig. 3 and which as indicated by Figs. 2 and 3 open on the forward end face 35 of the cylinder section 11. In the projections 31 of the member 29 I form passages 63 which lead from the sur-

face of the extension 31 in contact with the surface 35 to the end surfaces of the projections 31 so as to open into the chamber 33 and thereby conduct motive fluid to said chambers when said passages are moved into registry with the passages 61.

For exhausting motive fluid from the chambers 33 I herein provide the projections 31 of the member 29 with passages 10 65 which when the member 29 is at the limits of its travel cause one or the other of the chambers to be placed in communication with the adjacent chamber 57 and consequently in communication with the atmosphere.

Generally stated the operation of the device described is as follows:—

With the parts in the position shown in Figs. 1 and 2 motive fluid is supplied by 20 way of the passages 49 and 51 to the upper chamber 45, whilst the lower chamber 45 is connected to the atmosphere by way of the groove 55, passage 53, chamber 57 and passage 59 as shown at the lower right hand corner of Fig. 2, and consequently the block 25 tends to move downwardly with relation to the member 29 which by reason of the mounting of the block on the pins 41 causes the member 29 to move towards one of its 25 extreme positions. Assuming the member 29 is moved to its right hand extreme position as viewed in Fig. 2 the passages 61 and 63 for the right hand projection 31 are moved into registry which supplies the right 30 hand chamber 33 with motive fluid, and as at this time the left hand projection 31, as viewed in Fig. 2, is at the extreme of its movement to the right the left hand passage 65 is placed in communication with the corresponding chamber 59 and in consequence 35 the member 29 is forced to the left as viewed in Fig. 2. This causes further movement of the block 25, and when the block 25 reaches the lower limit of its travel as 40 viewed in Fig. 2 motive fluid is admitted to the lower chamber 45 and exhausted from the upper chamber 45 in a manner similar to that by which it was admitted to the upper chamber 45 and exhausted from the lower 45 chamber 45 which causes further movement of the block 25. When the member 29 moves to the left hand limit of its travel motive fluid is admitted to the left hand chamber 33 and exhausted from the right hand chamber 33 which causes continued movement 50 and brings the parts again into the position shown by Fig. 2, which completes the cycle. By so arranging the parts I may obtain suitable pre-admission, compression and exhaustion of the motive fluid and cause the motive fluid to act in one chamber expansively while it is being admitted to the next successive chamber supplied.

It will be observed that the external teeth 65 23 on the chuck and the internal teeth 27 on

the block 25 form a reduction gear, which in consequence the gyratory motion of the block 25 is effective to rotate the chuck at a speed much less than the speed of gyration of the block 25.

Although I have described for purposes of illustration one specific embodiment of my invention it is to be understood that within the scope of my invention wide deviations may be made therefrom without departing 75 from the spirit of my invention.

Claims—

1. A rock drill having in combination a cylinder, a hammer piston in said cylinder, a chuck casing carried at the forward end of said cylinder, said chuck casing having a bore, a tubular chuck fitting said bore and being rotatably mounted therein, said chuck at its rearward end having a continuous series of external gear teeth, a pair of members surrounding said gear teeth one of which is mounted inside the other for reciprocation relatively thereto, means other than said gear teeth on said chuck for positively enforcing a reciprocatory motion of one of said members and a gyratory motion of the other member, a continuous series of internal gear teeth carried by said member limited to a gyratory motion, said last named gear teeth meshing with said external gear teeth, and means for causing said motion of said members by fluid pressure.

2. A rock drill having in combination a cylinder, a hammer piston in said cylinder, a chuck casing carried at the forward end of said cylinder, said chuck casing having a bore, a tubular chuck fitting said bore and being rotatably mounted therein, said chuck at its rearward end having a continuous series of external gear teeth, a member mounted for gyration and having a continuous series of internal gear teeth meshing with said gear teeth carried by said chuck, eccentric mechanism enforcing gyratory movement of said member, a member mounted for reciprocation and relatively to which member said first named member is mounted for reciprocation, and means for causing conjoint motion of said members by fluid pressure.

3. A rock drill having in combination a cylinder, a hammer piston in said cylinder, a chuck casing carried at the forward end of said cylinder, said chuck casing having a bore, a tubular chuck fitting said bore and being rotatably mounted therein, said chuck at its rearward end having a continuous series of external gear teeth, a fluid pressure motor for rotating said chuck, said motor comprising a pair of members one of which is mounted on the other for reciprocation, guiding means for causing one of said members to have a reciprocatory motion and other guiding means for causing the other member to have a gyratory motion, and

means independent of said guiding means for directly gearing the last mentioned of said members to said chuck.

4. In a rock drill, a cylinder, a hammer piston in said cylinder, a rotary chuck carried by said cylinder and formed for carrying a drill steel operated by said hammer piston, a fluid pressure motor for rotating said chuck, said motor comprising a pair of members one of which is mounted on the other, guide means for causing one of said members to reciprocate transversely to said chuck, eccentric mechanism for causing the other of said members to have a gyratory motion, and means independent of said guide means for directly gearing the last named member to said chuck.

5. In a rock drill, a cylinder, a hammer piston in said cylinder, a rotary chuck carried by said cylinder and formed for carrying a drill steel operated by said hammer piston, a fluid pressure motor for rotating said chuck, said motor comprising an inner member and an outer member, said inner member carrying gear teeth meshing with gear teeth carried by said chuck, eccentric mechanism for causing said inner member to have a gyratory motion around the axis of said chuck, said outer member surrounding said inner member and on which said inner member is mounted for relative reciprocation, and guide means for causing said outer member to reciprocate transversely to said chuck and transversely to said relative reciprocation.

6. In a rock drill, a cylinder, a hammer piston in said cylinder, a rotary chuck carried by said cylinder and formed for carrying a drill steel operated by said hammer piston, a fluid pressure motor for rotating said chuck, said motor comprising an inner member and an outer member, said inner member carrying internal gear teeth meshing with external gear teeth carried by said chuck, eccentric mechanism for causing said inner member to have a gyratory motion around the axis of said chuck, and said outer member surrounding said inner member and on which said inner member is mounted for relative reciprocation, and guide means for causing said outer member to reciprocate transversely to said chuck and transversely to said relative reciprocation.

7. In a rock drill, a cylinder, a hammer piston in said cylinder, a rotary chuck carried by said cylinder and formed for carrying a drill steel operated by said hammer piston, a fluid pressure motor for rotating said chuck, said motor comprising an inner member and an outer member, said inner member surrounding said chuck and carrying gear teeth meshing with gear teeth carried by said chuck, eccentric mechanism for causing said inner member to have a gyratory motion about said chuck, said outer

member surrounding said chuck and said inner member and on which said inner member is mounted for relative reciprocation, and guide means for causing said outer member to reciprocate transversely to said chuck 70 and transversely to said relative reciprocation.

8. In a rock drill, a cylinder, a hammer piston in said cylinder, a rotary chuck carried by said cylinder and formed for carrying a drill steel operated by said hammer piston, a fluid pressure motor for rotating said chuck, said motor comprising an inner member and an outer member, said inner member surrounding said chuck and carrying internal gear teeth meshing with external gear teeth carried by said chuck, eccentric mechanism for causing said inner member to have a gyratory motion about said chuck, said outer member surrounding said chuck and said inner member and on which said inner member is mounted for relative reciprocation, and guide means for causing said outer member to reciprocate transversely to said chuck and transversely to said 80 relative reciprocation.

9. In a rock drill, a casing containing a hammer piston and a rotary chuck, said casing having mounted therein for reciprocation transversely of said chuck a member which surrounds said chuck, a second member surrounding said chuck and mounted in said first mentioned member for reciprocation relatively to said first mentioned member and transversely to the reciprocation of said first mentioned member, a plurality of eccentric supports for said second member rotatably mounted in said casing, a direct gearing connection between said second member and chuck, and means for causing motive fluid to act upon said members for giving motion to said members.

10. In a rock drill, a casing containing a hammer piston and a rotary chuck, said casing having mounted therein for reciprocation transversely of said chuck a member which surrounds said chuck, a second member surrounding said chuck and mounted in said first mentioned member for reciprocation relatively to said first mentioned member and transversely to the reciprocation of said first mentioned member, a plurality of eccentric supports for said second member rotatably mounted in said casing, a direct gearing connection between said second member and chuck, and means for causing motive fluid to act upon at least one of said members for giving motion to said members.

11. In a rock drill, a casing containing a hammer piston and a rotary chuck, said casing having mounted therein for reciprocation transversely of said chuck a member which surrounds said chuck, a second member surrounding said chuck and mount-

ed in said first mentioned member for reciprocation relatively to said first mentioned member and transversely to the reciprocation of said first mentioned member; a plurality of eccentric supports for said second member rotatively mounted in said casing, a direct gearing connection between said second member and chuck, and means for permitting motive fluid to act between said members and between said first mentioned member and the casing for giving motion to said members.

12. In a rock drill, a casing containing a hammer piston and a rotary chuck, said casing having mounted therein for reciprocation transversely of said chuck a member which surrounds said chuck, a second member surrounding said chuck and mounted in said first mentioned member for reciprocation relatively to said first mentioned member and transversely to the reciprocation of said first mentioned member, a plurality of eccentric supports for said second member rotatably mounted in said casing and surrounded by said first mentioned member, and means for causing motive fluid to act upon at least one of said members for giving motion to said members.

13. In a rock drill, a casing, a chuck ro-

tatably mounted in said casing and formed for carrying a drill steel, a piston for operating said drill steel, a fluid pressure motor for rotating said chuck, said motor comprising a gyratory member mounted upon a plurality of spaced independent eccentric members, said eccentric members rotatably carried by said casing, guiding means for preventing rotation of said gyratory member, said eccentric members rotated in unison solely by said gyratory member, and means for causing said gyratory member to drive said chuck.

14. In a rock drill, a casing, a chuck rotatably mounted in said casing and formed for carrying a drill steel, a piston for operating said drill steel, a fluid pressure motor for rotating said chuck, said motor comprising a gyratory member mounted upon a plurality of independent eccentric members, said eccentric members rotatably carried by said casing, guiding means surrounding said gyratory member for preventing rotation of said gyratory member, and means for causing said gyratory member to drive said chuck.

In testimony whereof, I have signed my name to this specification.

GEORGE H. GILMAN.
